UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 35,895, dated May 6, 1902.

Application filed March 27, 1902. Serial No. 100,332. Term of patent 3½ years.

To all whom it may concern:

Be it known that I, GEORGE W. BLAIR, of Pittsburgh, Allegheny county, Pennsylvania, have invented and produced a new and original Design for a Lamp-Chimney, of which the following is a full, clear, and exact description, reference being had to the accompanying drawings, forming part of this specification, in which—

10 Figure 1 is a side elevation of a lamp-chimney embodying my design, and Fig. 2 is a top plan view of the same.

15 The essential feature of my design consists in a lamp-chimney having a body provided with a series of longitudinally-extending strips of crystal glass which are separated by portions of semi-opaque or translucent glass having a wrinkled or wavy surface.

In the drawings I show a lamp-chimney having a body of globular form. This body is 20 provided with a series of vertical strips 2 of crystal glass, between which are semi-opaque or translucent portions 3, having a wavy or wrinkled surface. I show the crystal strips as having a series of bosses 4. 25

I claim—

The design for a lamp-chimney substantially as herein shown and described.

In testimony whereof I have hereunto set my hand.

GEORGE W. BLAIR.
